UNITED STATES PATENT OFFICE

2,423,525

ELECTRIC LAMP

Grover C. Singer, Brownsville, Tex.

Application February 13, 1945, Serial No. 577,654

2 Claims. (Cl. 176—34)

1

This invention relates to electric lamps.

An object of the invention is the provision of an electric lamp adapted for particular use in headlights of automobiles in which a reflecting disk is located centrally of the outer end of a transparent globe formed integrally with a base, the bottom of the globe being provided with a reflecting surface extending outwardly along the inner side walls of the globe and an additional reflecting surface projecting outwardly from the bottom of the globe and below the disk and in association with filaments.

Another object of the invention is the provision of an electric lamp including a globe and base member formed of transparent materials with the outer end of the globe being substantially flattened and providing a reflecting disk for eliminating direct blinding rays from the filaments included in the globe.

A further object of the invention is the provision of an electric lamp including a globe and an integrally formed base member, an extension rising from the bottom of the globe and provided with reflecting materials located directly under a disk formed of reflecting materials and located on an outer flat face of the globe.

Another object of the invention is the provision of an electric lamp including a bulb and integrally formed base member which is provided with a central longitudinal passage, said passage being closed by a plug having a hollow portion extending into the globe with reflecting materials applied to certain of the walls of the hollow portion, said hollow portion of the plug being located directly beneath a disk of reflecting materials which is applied to the inner face of a flat outer end portion of the globe.

This invention will be best understood from a consideration of the following detailed description, of the accompanying drawings forming a part of the specification; nevertheless, it is to be understood that the invention is not confined to the disclosure, being susceptible of such changes and modifications as define no material departure from the salient features of the invention as expressed in the appended claims.

In the drawings:

Fig. 1 is a horizontal section of an electric lamp taken along the line 1—1 of Fig. 2.

Fig. 2 is a vertical section taken along the line 2—2 of Fig. 1.

Fig. 3 is a vertical section similar to that shown in Fig. 2, but of a modified form of the electric lamp.

2

Fig. 4 is a vertical section of another modified form of the electric lamp.

Figs. 5 and 6 are vertical sections of still other forms of the electric lamp.

5 Fig. 7 is a fragmentary vertical section of a lamp showing a hollow chamber on the inner end of a plug sealed within a passage of the base member.

Referring more particularly to Figs. 1 and 2, it will be seen that 10 designates a base member which is formed integrally with a globe 11 formed of transparent materials. The outer end of the globe as shown at 12 is substantially flat and is formed independently of the globe. The member 12 is fused on to the outer edge of the globe 11.

The base member 10 is provided with an axial passage 13 in which is mounted a plug 14. This plug is sealed to the walls of the passage 13 and has a centrally disposed passage 15 for the purpose of withdrawing the air from the globe 11 in the usual manner. After the air has been exhausted from the globe this passage is sealed.

The inner side wall of the globe 11 is coated with a reflecting material 17 as is the bottom 18 of the bulb as shown at 19. A disk 20 formed of reflecting materials is secured by fusing or cementing it to the inner face of the member 12 directly over the plug 14, in order to reflect back strong light rays, and thus eliminate a concentrated light forwardly of the automobile.

35 A substantially semi-spherical element 23 is located within the globe 11 and the flat bottom 24 of said element is sealed to the reflecting materials 19 on the bottom of the globe 11. The element 23 presents a substantially rounded surface to the outer end 12 of the globe. It will be noted that the passage 15 is continued through the element 23 as shown at 25, since all of the parts of the lamp must be assembled before the bulb 11 is exhausted.

40 The filaments 30 and 31 are supported between the respective posts 32, 33 and 34. Filaments 35 and 36 are supported between the respective pairs of posts 37—38 and 39—39. In 45 each case the post 33 forms a common support for both the filaments 30 and 31 while post 38 forms a common support for filaments 35 and 36.

It will be noted that wires 40 and 41 are connected to the respective contacts 42 and 43, while 50 wire 44 is imbedded in the base member 10 and is connected with a threaded sleeve 45 which surrounds the reduced portion 46 of the base member 10.

It will be noted that the wires 40 and 41 extend through the respective posts 34 and 38, with

the outer ends of the wires being split as shown at 47 and bent over the outer ends of the hollow posts in order to maintain the posts in position.

A split lug 48 extending from the post 34 receives one end of the filament 31. A split lug 49 extending from the post 33 is adapted to clamp the other end of the filament 31.

A split lug 50 extending from the post 33 and a split lug 51 extending from the post 32 are clamped upon the opposite ends of the filament 30.

Since the posts 31, 38 and the split lugs connected with said posts are similar in construction to the arrangement shown at the left hand side in Fig. 1, the same reference numerals will be applied to the posts at the right hand side in Figs. 1 and 2, since the filaments arrangement and the supports on both sides of the bulb are identical in construction, except that the exponent *a* is applied to the numerals.

The construction and arrangement of the filaments, the lead-in wires, posts and the connections are described and illustrated in my Patent No. 2,368,685 of February 6, 1945.

The hemispherical member 23 which overlies the reflecting materials 19 on the flattened bottom 24 of the bulb will tend to project strong light rays forwardly, but due to the reflector 20 on the member 12 the centrally disposed light rays will be reflected back into the interior of the bulb.

Furthermore, the incurved side walls of the globe 11 will also tend to reflect rays rearwardly so that no strong light will be reflected from the lamp.

In Fig. 3 is shown a modified form of an electric lamp in which a base member 10^a is formed integrally with a bulb portion 11^a. The outer end or flat transparent cover plate 12 may be fused on to the outer end of the bulb 11^a or this cover plate may be formed integrally with the bulb, since the base portion 10^a has a central passage 60 which has a diameter sufficiently great so that all of the elements which are necessary to be placed in the bulb 11^a may be inserted through this passage which is closed by a plug 61, which may be formed of transparent materials. The cover plate 12 of the bulb is provided with a reflecting disk 20^a. Since the arrangement and elements for supporting the filaments are substantially the same as that shown in Figs. 1 and 2, the same reference numerals are applied to the respective elements.

The distinction between Fig. 3 and Figs. 1 and 2 resides in the plug 61 and the substantially conically shaped projection 62.

The inner end of the plug 61 is provided with a curved seat 63 upon which is mounted the projection 62 having reflecting materials 64 mounted on the bottom of the projection which is sealed to the seat 63 in any approved manner.

The plug 61 is provided with a central passage 65 which aligns with a central passage 66 formed in the projection 62 so that air may be exhausted from the bulb 11^a. This passage 65 is closed by the usual cement as shown at 67^a.

It will be noted that the projection 62 is not only conically shaped, but is corrugated as shown at 67^b, so that rays from the filaments which strike the corrugated section 67^b will be diffused and therefore eliminate any blinding rays from the lamp. Furthermore, the incurved side walls of the bulb 11^a which are covered with reflecting materials 19 will cooperate with the reflect-

ing disk 20^a for further aiding in eliminating blinding rays emanating from the lamp.

Referring more particularly to Fig. 4, it will be seen that the difference between this construction and that shown in Fig. 2 is the addition of the plug 70 and a chamber 71 formed in the inner end of the plug and located within the bulb 11^b. Since all of the other elements of the lamp are substantially the same as those shown in Fig. 2 the same reference numerals are applied thereto. However, the extension 72 of the plug 70 replaces the element 23 shown in Fig. 2.

The plug 70 is sealed to the walls of the central passage 13 in the base member 10^b. The plug has a narrow longitudinal passage 73 which opens at 74 in the chamber 71 into the interior of the globe 11^b for exhausting air from the globe. This passage is then sealed by the usual form of cement.

20 The inner end 72 of the plug 70 is provided with a chamber 71 and the inner top wall 75 of this chamber is curved as is the outer end 76 of the plug. The inner side wall of the chamber 71 and the bottom of the chamber is coated with reflecting materials as indicated at 77. The reflecting disk 20^b is located at the inner face of the flat closure 12^b on the outer end of the bulb 11^b and directly over the outer end of the plug 70.

It will be seen by this construction that light rays from the filaments are not only reflected by the reflecting materials 19 on the bottom 18 of the globe 11^b, but they are reflected by the reflecting materials on the side and bottom walls of the chamber 71. The reflecting materials 17 on the inwardly curved side walls of the bulb 11^b reflect light rays rearwardly and toward the projection 72 of the plug 70.

30 The various wires connecting the contacts 42 and the threaded sleeve 45 with the respective posts have the same reference numerals as do the wires illustrated in Figs. 1 to 3 inclusive.

40 Referring more particularly to Fig. 5, it will be seen that a modified form of the plug is employed. However, the lead-in wires, the posts and the filaments are identical in construction to those shown in Figs. 1 to 4 inclusive, and therefore the same reference numerals are employed. The plug 80 is received within the passage 13 in the base portion 10^c and is sealed therein. The inner end of the plug projects into the bulb 11^c and is provided with a chamber 81. The bottom of the chamber as shown at 82 is curved and is provided with reflecting materials indicated at 85, after which the member 83 is sealed in place.

50 It will be noted that the plug 80 and likewise the concavo-convex member 83 have the respectively aligned passages 86 and 87 so that air may be exhausted from the bulb 11^c. The passage in the plug 80 is closed by the usual form of cement.

60 Light rays from the filaments are reflected by the reflector 85 and due to the highly polished concave surface 84 of the member 83, said surface will also reflect the light rays. Light rays strike the reflecting materials 17 on the inner wall of the bulb 11^c and these rays are reflected inwardly due to the incurved walls of the bulb. Any intense rays which are reflected outwardly strike the reflecting disk 20^c, and these rays are returned so that the rays which are projected through the transparent cover plate 12^c will not have a blinding effect.

70 In view of the fact that the passage 13 in the base portion 10^c is relatively wide, the posts 32 to 34 inclusive, and 37 to 39 inclusive may be inserted through the passage and applied in posi-

tion. The plug 80 and the member 83 may be completely formed exteriorly of the lamp and inserted in position. Thus, the member 12^c may be formed integrally with the globe 11^c and the base 10^c.

Referring more particularly to Fig. 6, it will be seen that a modified form of the plug is employed in the passage 13 of the base portion 10^d which is formed integrally with the globe 11^d. The outer end 12^d of the globe may be formed integrally with said globe since the plug 90 is inserted into the passage 13.

The plug 90 extends into the globe 11^d as shown at 91, and the extended portion is provided with a chamber 92 in which are mounted posts 93 and 94 for carrying the filaments 95 at the upper ends of the posts. The bottom 96 of the chamber 92 is coated with reflecting materials as indicated at 97.

A wire 98 connects the contact 99 at the outer end of the plug to the post 94. A wire 100 is embedded in the plug 90 as is the wire 98 and extends upwardly into the chamber 92 and is connected to the post 93. The wires 98 and 100 have split ends which are bent over the outer ends of the posts 94 and 93 for retaining the posts in position as shown more particularly in Fig. 3. The lower end of the wire 100 is connected to a strip of metal 101 which is embedded in the plug 90 so that there will be sufficient contacting surface for the short wire 102 embedded in the base 10^d to make electrical contact with the wire 100. The wire 102 is in contact with the threaded sleeve 45.

Referring more particularly to Fig. 7, it will be seen that a fragmentary bulb is shown having a base member 10^e formed of transparent materials and integrally formed with a globe 11^e. A plug 105 is located within a central passage 106 in the base 10^e and is sealed thereto. This form of lamp is substantially the same as that shown in Fig. 6, except that the walls 107 of the chamber 108 are progressively divergent from the bottom to the outer end and the side walls are corrugated instead of being straight as shown in Fig. 6. The rest of the elements shown in Fig. 7 are identical with those shown in Fig. 6, and therefore the same reference numerals will be applied. In this case, however, the inner side walls of the chamber 108 are coated with reflecting materials 109.

In all of the constructions it will be seen that the lamp uniformly contains the reflecting disk 20 at the outer and inner side of the outer end of the globe for reflecting rearwardly intense rays from the filaments. The lamps further are provided with interior reflectors at the center of the base of the globe directly beneath the disk 20 20^a, 20^b, or 20^c as the case, may be for spreading the rays outwardly to the side walls of the globe which are likewise provided with reflecting materials for aiding in eliminating any blinding rays from the lamp. It will also be noted that the

reflecting materials have been eliminated on sections of the base member where the posts which are formed of conductive material are mounted on said base in order to prevent short circuiting.

5 In Figure 6, the extension 91 may be made of colored glass and the disk 20 may be a colored insert. The colors will aid in reducing the glare of the lamp.

10 The members 62, 91, 81 and 108 may be made of china.

I claim:

15 1. An incandescent electric lamp comprising a globe having a tubular base, a filament, a plug of colored glass hermetically sealed within the base having an inner end projecting into the bulb and provided on its end with a reflecting coating, a reflecting coating provided on the side walls of the bulb only to a point above the end of the plug, and an opaque reflecting surface at the center 20 of the outer end of the bulb in alignment with the filament and the reflecting surface on said inner extension, whereby those light rays passing through the colored glass and falling on the reflecting surface of the side walls of the bulb and those reflected from the central reflecting surfaces at the center of the bulb and the end of 25 said plug will be projected outwardly through the clear space of the outer end of the bulb together with the normal rays from the filament to provide 30 a soft light glow emanating from the lamp.

2. An electric lamp comprising a bulb having a flat inner bottom, side walls curving inwardly therefrom and a flat top parallel to said bottom, a tubular stem extending outwardly therefrom, 35 a filament within the bulb, a plug of transparent material sealed within the stem having an inner end projecting into the bulb, reflecting coatings on the bottom and side walls of the bulb, a similar surface on the inner end of the plug above the flat bottom of said bulb and an opaque reflecting surface on the inner side of the flat top of the bulb in line with the reflecting surface on the end of said plug.
